UNITED STATES PATENT OFFICE.

MILTON TIBBETTS, OF DETROIT, MICHIGAN, ASSIGNOR TO PACKARD MOTOR CAR COMPANY, OF DETROIT, MICHIGAN, A CORPORATION OF MICHIGAN.

ENGINE.

1,272,323.

Specification of Letters Patent. Patented July 9, 1918.

Original application filed March 18, 1909, Serial No. 484,231. Divided and this application filed May 4, 1914. Serial No. 836,284.

To all whom it may concern:

Be it known that I, MILTON TIBBETTS, a citizen of the United States, and resident of Detroit, Wayne county, State of Michigan, have invented certain new and useful Improvements in Engines, of which the following is a specification.

This application is a division of co-pending application Serial No. 484,231, filed 10 March 18, 1909, and relates to engines in the broadest sense, including motors of all kinds, compressors and blowing engines, pumps and similar devices and particularly to internal combustion motors employing 15 sliding valves.

Engines have heretofore been constructed in which the inlet and outlet ports are arranged opposite each other and in approximately the same plane and in which a pair 20 of sleeves surround the piston and have co-operating ports to open and close the cylinder ports, and it is improvements upon and additions to such motors that constitute the subject matter of my present invention.

One of the objects of my invention is to provide a valve mechanism that is simple in construction and positive in operation.

Another object of my invention is to obtain a larger, quicker, and more positive 30 opening and closing of the inlet and exhaust ports of the engine than has heretofore been accomplished.

These and other objects will appear in the following description taken in connection 35 with the drawings, in which:—

Figure 1 is a transverse sectional view through the center of the cylinder of an engine embodying some of the features of my invention;

Fig. 2 is a section on the line 2—2 of Fig. 1;

Fig. 3 is a transverse sectional view, similar to Fig. 1, of an engine embodying another form of my invention; and

Fig. 4 is a section on the line 4—4 of Fig. 3.

In one form of the invention shown in the drawings, the valve mechanism comprises two sleeve valves arranged end to end in the 50 cylinder.

In another form of the invention, the valve mechanism comprises two concentric sleeve valves, one of which is adapted to cover and uncover the inlet and outlet ports

and the other of which is adapted to control 55 one only of said ports.

Referring to the drawings 20 represents the casing or cylinder of the engine having double walls forming a water jacket 21. This casing is mounted on the upper or supporting section 22 of the crank case and the crank shaft 23 is mounted in bearings 24 between said section and the removable intermediate section 25. The bottom of the 60 crank case is closed by the removable cover 26 which forms an oil well into which the cranks 27 dip as they revolve, thus lubricating, by the splash system, the various working parts within the crank case.

Also mounted to rotate in the supporting 70 section 22 parallel with the crank shaft is a valve operating shaft 28 having eccentrics or cranks 29 for reciprocating the valves hereinafter described. This shaft 28 is driven by the crank shaft by two-to-one 75 gearing such as illustrated in the drawing and hereinafter described whereby the motor is operated on the four stroke cycle.

The upper end of the casing or cylinder 20 is closed by a removable end wall or head 30, the cylindrical shaped central part 31 of which extends down into the casing as shown, leaving an annular space 32 between its periphery and the inner wall of the casing. This head is also water jacketed as 80 shown, its water jacket being connected with the jacket 21 of the cylinder, and it is formed with horizontal ports 33, which nearly divide it, the lower part 34 being suspended only by the hollow arms 35 85 through which the water passes to the jacket 36. The said lower part 34 is in the form of a hollow ring with the ports 33 along its upper edge and thus these ports are in constant communication with the interior of the 90 casing or cylinder 20. A spark plug 37 is provided in the central part of the head for igniting the charge in the cylinder, as is well understood.

The casing or cylinder 20 is formed with 100 inlet and exhaust chambers 38 and 39, which extend parallel with each other entirely around the casings, being separated by a thin partition 40. The inlet chamber 38 communicates with the inlet pipe 41 and 105 with the ports 42 in the casing wall, which ports are arranged approximately in a plane with the ports 33 in the head above de-

scribed, and the exhaust chamber 39 communicates with the exhaust pipe 43 and with the ports 44 in the casing wall, which ports 44 extend practically around the cylinder 5 and are arranged just below the lower edge of the part 34 of the head above described.

It will be understood that with the above arrangement of chambers and ports the total area of the ports will be greater than 10 in engines employing opposite inlet and outlet ports where each port extends less than half way around the cylinder, and when the engine is used as an explosive motor the 15 hot exhaust gases passing through the exhaust chamber, will tend to warm the gases entering the inlet chamber.

Referring particularly to Figs. 1 and 2, it will be seen that guided by the inner wall 20 of the casing and arranged co-axially and end to end are two sleeves, the upper sleeve 100 moving up and down in the annular space 32 between the head 30 and the inner wall of the casing to close the inlet port 42 and the lower sleeve 101 surrounding the 25 piston and moving down and up to open and close the exhaust port 44. The upper sleeve is reciprocated by rods 102 which are connected to ears 103 on the sleeve, and extend down through vertical guidways 104 30 into the crank case where their lower ends are connected by rods 105 with cranks or eccentrics 29 on the valve operating shafts. The lower sleeve is connected through ears 106 and rods 107 with its respective cranks 35 or eccentrics on the shafts, as will be clearly seen. In this form of the invention I have shown two operating shafts, one on each side of the motor, and they are identical in construction and are rotated by two-to-one-gearing from the crank shaft, such as 40 large gears 108 and small gear 109. The use of two operating shafts guards against twisting or binding of the sleeves that might occur if only one shaft were used.

Referring to Figs. 3 and 4, it will be seen that guided by the inner wall of the casing 20 and extending into the annular space 32, is a sliding valve shown in the form of a cylindrical sleeve 50^a, having two 45 sets of ports 51 and 52, each of which sets extends entirely around the sleeve, the sections above and below the ports being connected by webs. The ports 51 are adapted to register with the inlet ports 42 and consequently with the port 33 in the head 30 50 and the ports 52 are adapted to register with the exhaust port 44.

Surrounding the sleeve 50^a is an outer sleeve 53^a which is shorter than the inner sleeve and co-operates therewith only in controlling the lower or exhaust ports, the inner sleeve alone controlling the inlet ports. Except as stated and as to a slight difference in the timing of the sleeves made necessary by their construction, this motor is 65

similar to the other form and like parts are similarly designated.

The periphery of the central part of the head is provided with split packing rings above and below the ports whereby the ports 70 are made tight when said ports are over these rings which is preferably during the compression and firing strokes of the motor.

It is evident that the ports and passages may be formed in the cylinder and sleeves 75 in various ways and the invention is not limited to the specific forms shown.

Having thus described my invention, what I claim and desire to secure by Letters Patent is:—

1. The combination with a casing having a head extending into one end thereof and a working piston in the casing, of a single sleeve valve between the extended part of the head and the surrounding casing, and 85 another sleeve valve between the piston and the casing, and means for operating said valves.

2. The combination with a casing having a head extending into one end thereof and 90 a working piston in the casing, of a single sleeve valve between the extended part of the head and the surrounding casing, and another sleeve valve between the piston and the casing, and positive means for operating 95 said valves.

3. The combination with a casing having a working piston therein and formed with inlet and outlet ports arranged axially beyond one end of the path of travel of the 100 piston and an annular unobstructed valve chamber coaxial with the piston, of a plurality of open ended sleeve valves relatively movable and arranged end to end in said chamber for controlling said ports, and 105 means for actuating the said valves.

4. The combination with a cylinder having a working piston therein and formed with inlet and exhaust ports at one end thereof, of a pair of sleeve valves concentric with the cylinder axis, one sleeve controlling the inlet and the other the exhaust port, and means for actuating said sleeves including a connection to one sleeve at the head end of the cylinder and a connection 110 to the other sleeve at the opposite end of the cylinder.

5. The combination with a cylinder having a fixed cylinder head and a working piston therein, said cylinder formed with 115 inlet and outlet ports at one end thereof, of a pair of sleeve valves concentric with the cylinder axis for controlling said ports, and means for actuating said sleeve including a connection to one sleeve at the head 120 end of the cylinder and a connection to the other sleeve at the opposite end of the cylinder.

6. The combination with a crank case 125 and a cylinder carried thereby having a 130
